(57) **CLAIM**

We claim the ornamental design for a badge, as shown and described.

DESCRIPTION

FIG. 1 is a perspective view of a badge, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded, front-perspective view of thereof; and,

FIG. 9 is an exploded, rear-perspective view thereof.

The broken lines depict portions of the badge and form no part of the claimed design. The other broken lines in FIGS. 3 and 9 represent surface indicia and form no part of the claimed design.

1 Claim, 7 Drawing Sheets
